UNITED STATES PATENT OFFICE.

TIMOTHY J. HICKEY, OF PITTSBURG, PENNSYLVANIA, ASSIGNOR OF ONE-HALF TO ALPH AYMOND, OF ST. CHARLES, MISSOURI.

CAR-DOOR.

SPECIFICATION forming part of Letters Patent No. 393,155, dated November 20, 1888.

Application filed February 6, 1888. Serial No. 263,112. (No model.)

To all whom it may concern:

Be it known that I, TIMOTHY J. HICKEY, a citizen of the United States, residing at Pittsburgh, in the county of Allegheny, State of Pennsylvania, have invented certain new and useful Improvements in Car-Doors, of which the following is a specification, reference being had therein to the accompanying drawings.

This invention has relation to sliding doors for freight-cars, and among the objects in view is to provide a door so mounted as to be capable of being closed flush with the walls of the car and of being opened and slid to one side and in a plane outside of the walls thereof. Further objects of the invention are to secure these advantages with as few parts as possible, thus rendering the door simple, strong, and durable, and not liable to become damaged and inoperative, and also to provide convenient and simple means for opening and closing the door.

Other objects and advantages of the invention will hereinafter appear, and the novel features of the invention will be particularly pointed out in the claims.

Referring to the drawings, Figure 1 is a side elevation of a portion of a freight-car provided with a door constructed in accordance with my invention, the same being shown in a closed and locked position. Fig. 2 is a transverse section on the line $y-y$ of Fig. 1, the door being unlocked and in position for opening. Fig. 3 is a similar view, the door being swung out from the car and in position to be slid to one side thereof. Fig. 4 is a vertical section in detail on the line $x-x$ of Fig. 1.

Similar letters of reference indicate like parts in all the figures of the drawings.

A represents the side of the car, which is of the usual construction and provided with the door-opening A' and vertical side posts, A² A³, which form the door-frame, the former being transversely recessed, as at A⁴, and the latter vertically recessed, as at A⁵, to receive the rear edge of the door B, which door is adapted to fit snugly in position within the opening A'.

B B' represent, respectively, the upper and lower rails, which run longitudinal the car and above and below the door-opening A'. The

upper rail, B, is slightly below the upper edge of the door-opening, and is preferably held in position by means of an ordinary space-beam, B⁶, (see dotted lines,) to which it is securely bolted by bolts B⁸. The lower rail is 55 mounted in position by being secured to brackets B⁴, which project laterally from the side of the car. That bracket B⁴ opposite the post or beam A² is slanting and mounted flush with the lower edge of the door opening or sill, and 6c the track B' which it aids in supporting is held in position so that its upper edge is slightly above the plane of said sill and is formed with a recess, B⁵, in its said edge at that point thereof directly above the bracket just described. It will be noticed that each of the tracks B B' are curved or inwardly disposed, as at B⁶, at a point about midway and opposite the door C and upon the lower track, and at or about a point thereon where the inward 70 curve terminates is supported the rear edge of the door C by means of an outwardly-projecting bracket, C', which is laterally slotted in its under surface, as at C², and embraces the upper edge of said track. A similar bracket 75 projects from the door C at its opposite edge, and when the door is closed flush with the wall of the car said bracket rests upon the bracket B⁴, which, as before described, is flush with the sill of the door. 80

As shown in Fig. 4 of the drawings, the bracket B⁴ may be recessed at a point thereof in front of the bracket C' of the door, into which is adapted to be inserted a wedge-shaped or other retaining-pin, C³, by which the door 85 is prevented from rattling, and which also serves as a means of retaining the door in a closed position when it would be inconvenient or unnecessary to employ the ordinary locking means hereinafter described. 90

Within the recess A⁴ formed in the post A² is seated a hasp-plate, D', in which is pivoted a hasp, D, which is slotted at its forward end and adapted to be swung over a staple, D³, driven in the door and is provided back of its 95 pivot with a curved tongue or arm, D². The location of the hasp-lever is such that when swung open so that its forward or hasp end projects forward its rear or curved end is brought in contact with a wearing-plate, C⁴, 100

formed on the front end of the car-door. By pressing the front end of the lever toward the side of the car the curved end thereof forces the front edge of the door C outwardly until the notched bracket C' has ridden down the inclined bracket B' and straddles the track B'. Now, by grasping the handle and pushing, the door can be slid to one side of the car and the opening made clear for the removal or reception of freight. As the door is slid to one side its top edge is embraced by the upper track, B, and the brackets C' of the door embrace the upper edge of the lower track, B', and said tracks being curved the door is brought out of a plane with the sides of the car and may be slid out of the way. When the door is being slid to one side, the lever D assumes the position shown in Fig. 3 and performs another important function, in that it prevents the door from marring the side of the car. To close the door, the same is simply slid in an opposite direction until the curved ends of the tracks cause the rear edge of the door to take into the vertical recess A⁵, formed in the post A³, when, by a slight pressure, the door can be pressed back into the opening and flush with the outer wall of the car and behind the beam B⁸, which depends

slightly below the door-opening. The lever D is now swung to the locking position, so that the slot in the end thereof takes over the hasp D³, when said door may be securely locked by the employment of any ordinary padlock. 30

Having described my invention and its operation, what I claim is— 35

1. The combination, with the door C, having the slotted bracket C', with the inclined bracket B⁴, having a recess, and the removable pin C⁶, adapted to enter said recess, substantially as specified. 40

2. The combination, with the door C, having the projecting bracket C', of the inclined supporting-brackets B⁴ B⁴⁸, carrying the track B', having the recess B⁵, substantially as specified. 45

3. The combination, with the door-post A², recessed in its inner face, as at A⁴, and having the plate D' set therein and provided with the pivoted locking-lever D, of the door C, having the wearing-plate C⁷, secured to its edge adjacent to the post, substantially as specified. 50

In testimony whereof I affix my signature in presence of two witnesses.

TIMOTHY J. HICKEY.
